UNITED STATES PATENT OFFICE.

VIRGINIA M. HOLLYDAY, OF BALTIMORE, MARYLAND.

ATTACHMENT FOR CHAIRS.

No. 810,277.

Specification of Letters Patent.

Patented Jan. 16, 1906.

Application filed April 4, 1905. Serial No. 253,768.

To all whom it may concern:

Be it known that I, VIRGINIA M. HOLLYDAY, a citizen of the United States, and a resident of Baltimore, in the State of Maryland, have 5 made an Improved Attachment for Chairs, of which the following is a specification.

My invention is an improved attachment for chairs for facilitating conversation between persons whose hearing is impaired. I 10 apply speaking-tubes to a double chair or seat, which is preferably of the vis-à-vis type, in such manner that persons seated on opposite sides of the central support or division between the seats may converse by means of the 15 speaking-tubes while supported comfortably and even while their hands may be used for work, since they are not required to support a mouthpiece or ear-tube.

The construction and arrangement of my 20 improved attachment is as hereinafter described, reference being had to the accompanying drawings, in which—

Figure 1 is a perspective view of a double or vis-à-vis seat provided with the attachment. 25 Fig. 2 is a horizontal section of the portion of the chair or seat provided with the attachment. Fig. 3 is a plan view illustrating a modification.

In Figs. 1 and 2, A and A' indicate a double chair or seat of the vis-à-vis type, the fronts and backs of the same being respectively on opposite sides. My invention is applied to the portion B of the frame which intervenes or separates the two seats, and in this 35 instance it is an attachment in the form of a horizontal bar C, having lateral projections c', the same conforming in arrangement and curvature to the frame B, to which it is secured. The ends of the bar C are turned down and 40 secured permanently to the curved frame B, and a post c' supports the central portion of the bar. At the point of junction of said post with the bar C two lateral projections c are arranged, the same extending in opposite directions and each forming a part of my improved attachment—that is to say, a passage c' extends from one side of each lateral projection c through the base of the same and through the connected portion of the bar C. 45 The termini of the passages are indicated by x and y, respectively, x being the enlarged or flared end into which a person speaks and y being the end at which the ear of the other person is placed. By preference the projec-

tions c are so made or formed that they appear to be natural attachments of the chair-frame, and thus would not excite attention of the ordinary observer. It will be seen that two persons seated on the opposite seats A A' and whose hearing is too much impaired to 55 allow conversation in an ordinary tone may converse with great convenience by placing their mouths at the points x, in which case one ear will be opposite and adjacent to the point y, so that what is spoken by one person 60 is transmitted directly to the ear of the other in the same manner as when a portable ear-trumpet is used. Each person may conveniently lean his head against the adjacent portion of the bar C, so that it will be supported 65 without wearying him. The projections c are reduced at the inner end, thus forming tenons and shoulders whereby they are held firmly in a bore or socket of the bar C, and braced laterally, so that they will not be dislodged in 70 ordinary use. In case the chair be constructed in rustic form the projection c will be of the same character, and thus form ornamental and not obtrusive attachments.

In Fig. 3 I illustrate a modification in which 80 hearing and speaking tubes c' have a flexible extension provided with a tapered mouth-piece. The extensions are represented as pendant and may have a length of ten or twelve 85 inches or more, if desired.

For accommodation of persons of different size or height the seats A and A' may be provided with one or more cushions, which will be adjusted as required, or the portion to which the attachment is applied may be made 90 vertically adjustable, so as to accommodate itself to the persons occupying opposite seats.

What I claim is—

1. A double seat of the vis-à-vis type having a central support between the seats proper, 95 the same being provided with two passages serving as hearing and speaking tubes and having open mouths which project rearward on opposite sides of the central support so that each set of such mouths is available for hearing and speaking by the person occupying the contiguous seat, substantially as described.

2. An improved article of furniture, comprising a double seat having backs and an intervening or middle portion forming a continuation thereof, and a horizontal bar C forming a rigid attachment of such middle portion, and provided with passages opening on 100 105

opposite sides of the bar and arranged for convenience of use for hearing and speaking in the manner described.

3. A seat comprising two seats proper and
5 a rigid vertical frame intervening the same
and having at the top lateral projections each
provided with a passage opening at one end
on the rear side thereof or toward the back of

the contiguous seat, the opposite end of the
passage opening on the other side of the 10
frame, as and for the purpose specified.

VIRGINIA M. HOLLYDAY.
